UNITED STATES PATENT OFFICE.

GEORGE N. HINCHMAN, OF WEBSTER GROVES, MISSOURI, ASSIGNOR TO
STANDARD ADDING MACHINE COMPANY, OF ST. LOUIS, MISSOURI, A
CORPORATION OF MISSOURI.

ADDING-MACHINE.

No. 851,089.

Specification of Letters Patent.

Patented April 23, 1907.

Application filed July 25, 1906. Serial No. 327,705.

To all whom it may concern:

Be it known that I, GEORGE N. HINCHMAN, a citizen of the United States, residing at Webster Groves, in the county of St. Louis and State of Missouri, have invented a certain new and useful Adding-Machine, of which the following is such a full, clear, and exact description as will enable any one skilled in the art to which it appertains to make and use the same, reference being had to the accompanying drawings, forming part of this specification.

My invention relates to an adding machine, and more particularly to that class of adding machines in which the individual items, as well as the totals, are printed upon a strip or sheet of paper.

The object of my invention is to provide means for printing a symbol or character to distinguish the items from the totals. Heretofore in machines of the class above described a symbol or character has been printed adjacent to each total to distinguish the total from the items. According to my invention, however, I print adjacent to each item a symbol or character preferably polygonal in form, whereby the items and totals are distinguished and at the same time means is provided for facilitating the checking of the items.

In the accompanying drawings, which illustrate my invention applied to a machine like that shown in my prior applications Nos. 287,118 and 287,119 of November 13th, 1905, Figure 1 is a vertical central section through the upper and forward part of the machine; Fig. 2 is an enlarged view showing the gearing for controlling the item sign; and Fig. 3 is a view illustrating the work done by the machine.

Like marks of reference refer to similar parts in the several views of the drawings.

5 is the casing of the machine, within which is the usual frame work 6 for supporting the various parts.

7 are the adding wheels mounted upon a shaft 8 provided with a comb 9. Below the adding wheel shaft 8 is a shaft 10, upon which are mounted idle wheels 11 which 50 are adapted to mesh with the adding wheels

7. Meshing with the idle wheels 11 are intermediate wheels 12 mounted upon a shaft 13 provided with a comb 14, as shown in Fig. 2. The intermediate wheels 12 are driven by means of an axially movable wheel 15 moving upon an axle 16. The intermediate wheels 12 mesh with printing wheels 17 mounted upon a shaft 18. The adding wheel 7, idle wheels 11, intermediate wheels 12, driving wheel 15 and printing wheels 17 are indicated in dotted lines in Fig. 1. The operation of these wheels in adding numbers is identically the same as in my prior applications above referred to. The adding wheels 7 are normally out of mesh with the idle 65 wheels 11 so that when the individual items are placed in the machine by the operation of the keys, the printing wheels 17 will be positioned from the driving wheel 15 through the intermediate wheels 12 without in any way 70 affecting the adding wheels 7. After the number has been printed, however, the adding wheels 7 are moved into mesh with the idle wheels 11, so that when the printing wheels 17 are returned to zero on the operation 75 of the main handle of the machine, the individual item will be transferred into the adding wheels 7. In order to print the total the adding wheels 7 are thrown into mesh with the intermediate wheels 11 and are re- 80 turned to zero by the operation of the total key 20, thus transferring the sum from the said adding wheels 7 to the printing wheels 17. The individual items, as well as the totals, 85 are printed upon a strip of paper 21, which strip passes between the printing wheels 17 and the printing hammers 22. A printing hammer 22 is supplied for each printing wheel 17, and there is also an additional hammer for co-operation with the type for printing the item symbol, as will be hereinafter described. The printing hammers 22 are operated by means of a printing slide 23 in the usual manner. The strip of paper 21 is supplied from a spool 24 mounted on a shaft 25. 90 From the spool 24 the strip of paper 21 passes around a guide 26, thence between the printing hammers 22 and the printing wheels 17 and around a second guide 27 to the feed rolls 28 and 29, from which it passes out through 100

2

a discharge opening 30 at the top of the machine. The above described parts are like those in my prior applications above referred to and need not be more particularly described.

5 Loosely mounted on the shaft 10 is a disk 35 having a tooth 36 adapted to be engaged by the comb 9 of the adding wheel shaft 8. This disk 35 is provided with teeth which mesh with corresponding teeth on a second disk 36 loosely mounted on the shaft 13 of the intermediate wheels 12. The disk 36 is also provided with a finger 37 projecting between two fingers 38 on a disk 39 loosely mounted on the printing wheel shaft 18.

10 This disk 39 carries a type 40 for printing the symbol adjacent to each item. This symbol preferably consists of a polygonal figure and may be in the form of a lozenge containing the letter S, as shown in Fig. 3 of the drawing. This type 40 is arranged as shown in the drawing so as to normally be in the path of the hammer 22 and is held in this position by means of a pawl 41 pivoted on a shaft 42 and provided with a spring 43.

15 This pawl 41 engages with a notch 44 in the disk 39 to hold the type 40 in its normal position. The disk 39 is also provided with a notch 45 to hold the type 40 out of printing position when the total is taken. When the adding wheel shaft 8 is rotated to return the adding wheels 7 to zero and thus transfer the total to the printing wheels 17, the comb 9 will come in contact with the tooth 36 on the disk 35 and so rotate the said disk in the direction of the arrow in Fig. 2. This motion will be communicated to the disk 36 by means of the teeth on the said disk so as to move said disk in the direction of the arrow in Fig. 2. This movement will be communicated by the fingers 37 and 38 to the disk 39 so as to move the said disk on the shaft 18, and, consequently, move the type 40 downwardly so as to be out of the path of the printing hammer 22. When moved in this position the pawl 41 will engage with the notch 45 in the disk 39 so as to hold the type 40 out of printing position until the various wheels are returned to their normal position, when the comb 14 in the shaft 13 will engage 40 with a pin 46 on the disk 36, so as to return the type 40 to its normal or printing position. The pin 46 projects at both sides of the disk 36 and is adapted to come in contact with the comb 47 which forms the stop for the intermediate wheels 12.

45 It will be seen from the above that whenever an item is written into the machine the type 40 will remain in its normal or printing position and adjacent to each item printed 60 the type 40 will print a lozenge-shaped symbol or character 48, as shown in Fig. 3 of the drawing. When, however, the total is taken the type 40 will be moved out of printing

position so that the sign will not be printed adjacent to the total. In this manner the totals are readily distinguished from the items and in addition means is provided whereby the items may be checked over a number of times without liability of confusing the check marks. This is often necessary, especially in long columns of figures and with the ordinary method of writing items without an item symbol the check marks are liable to be confused. With a polygonal item symbol, however, such as I use, the items may be checked over a number of times without any liability of confusion, as a different side or angle of the item symbol may be used during each time of checking, thus, for instance, upon first checking the items the item check may be made against the upper left hand side of the item symbol. At the second checking it may be made against the upper right hand side, and so on, and after the sides have been returned the angles of the symbol may be utilized.

Having fully described my invention, what I claim as new and desire to secure by Letters Patent of the United States is—

1. In an adding machine, the combination with adding mechanism, of means for automatically printing an item symbol in conjunction with each individual item, said means being inoperative when printing a total.

2. In an adding machine, the combination with adding mechanism, of printing devices for printing individual items and totals, an auxiliary printing device for printing a symbol adjacent to each item, and means for preventing said auxiliary device from printing when taking the total.

3. In an adding machine, the combination with adding mechanism, of printing devices including an item symbol, means for transferring the total from said adding mechanism to said printing device, and connections operated by the transfer of the total for preventing said item symbol from printing.

4. In an adding machine, the combination with adding wheels, of printing wheels including an item symbol, means for transferring the total from said adding wheels to said printing wheels, and connections operated by the transfer of the totals for preventing said item symbol from printing.

5. In an adding machine, the combination with adding mechanism, of printing devices including an item symbol normally in printing position, means for transferring the total to said printing devices, connections operated by the transfer of the total for moving said item symbol out of printing position, and means for returning said item symbol to printing position.

6. In an adding machine, the combination with adding mechanism, of printing devices for printing individual items and totals, an auxiliary printing device for printing a polygonal symbol adjacent to each item, and means for preventing said auxiliary device from printing when taking the total.

In testimony whereof, I have hereunto set my hand and affixed my seal in the presence of the two subscribing witnesses.

G. N. HINCHMAN. [L. s.]
